(57) **CLAIM**

The ornamental design for an icon for a portion of a display screen, as shown and described.

DESCRIPTION

The FIGURE is a front view of an icon for a portion of a display screen showing my new design.

The broken line showing of the portion of the display screen is included for the purpose of illustrating environmental structure and forms no part of the claimed design.

1 Claim, 1 Drawing Sheet

Figure

UNITED STATES PATENT AND TRADEMARK OFFICE
CERTIFICATE OF CORRECTION

PATENT NO. : Des. 550,695 S
APPLICATION NO. : 29/240979
DATED : September 11, 2007
INVENTOR(S) : Mark E. Salvati

Page 1 of 3

It is certified that error appears in the above-identified patent and that said Letters Patent is hereby corrected as shown below:

The Title Page, showing an illustrative figure, should be deleted and substitute therefor the attach title page.

Delete drawing sheet 1 and substitute therefor the drawing sheet, consisting of figure as shown on the attached page.

Signed and Sealed this

Third Day of June, 2008

JON W. DUDAS
